UNITED STATES PATENT OFFICE.

MORTIMER B. MILLS, OF CHICAGO, ILLINOIS.

RAILROAD-SWITCH APPLIANCE.

SPECIFICATION forming part of Letters Patent No. 404,214, dated May 28, 1889.

Application filed December 20, 1888. Serial No. 294,126. (No model.)

To all whom it may concern:

Be it known that I, MORTIMER B. MILLS, a citizen of the United States, residing at Chicago, in the county of Cook and State of Illinois, have invented a new and useful Improvement in Railroad-Switch Appliances, of which the following is a specification.

My improvement relates to means for operating the switches in railroad-tracks, my principal object being to provide reliably-operating mechanism which may be readily actuated at any desired distance from the switch to be thrown by the employment of pneumatic or other force.

My invention consists in the general construction of my improved mechanism; and it also consists in details of construction and combinations of parts.

In the accompanying drawings, Figure 1 shows my improved mechanism in plan view with a pneumatic apparatus for operating it. Fig. 2 shows the same in sectional side elevation, and Figs. 3 and 4 are perspective views of details of construction.

The mechanism which is immediately connected with the switch (not shown) through the medium of a connecting-bar, A, is supported on a suitable base, which I provide in the form of a covered box, B, having laterally-extending perforated ears r^2 , through which it may be bolted to a head-block. (Not shown.)

C is an air-receiver, which, though it may involve any of various forms for my purpose, is preferred of the form shown, which comprises a rounded metal shell formed in two flanged parts, r and r' , which are bolted together around the flanges, the latter holding between them the edge of a flexible (preferably rubber) diaphragm, D, which may be strengthened about its center on opposite sides by metal plates q and q' , the first-named having an internally-threaded socket, q^2 , on its face. Each part r and r' has an opening, that in the latter to permit the connection of a pipe, p , which leads from air-pressure mechanism (an air-pump, not shown) in the inclosure or house from which the switches are operated, but which is not shown in the drawings, and that in the latter to permit a rack-rod, E, hereinafter described, to be screwed at

one end into the socket q^2 . The part r of the receiver-shell is bolted to a side of the box B in a position to cause the opening provided in it to coincide with an opening, o , in the side 55 of the box.

The rack-bar E extends through the opening o into the box B, and is supported therein on rollers n , and extending into the farther end of the box is a set-screw, m , which stops 60 the rack-bar and limits its movement, produced in the manner hereinafter described.

F is a rotary shaft extending through the box transversely thereof, and thus horizontally across the rack-bar E, being supported 65 in bearings in the sides beyond which the ends of the horizontal shaft project, as shown. The end of the shaft F at the side of the box nearest the switch may be formed into a tongue, l , Fig. 3, to be inserted into a socket, l' , 70 in a head, F' , Fig. 4, being secured therein by a pin, l^2 , passed transversely through the head and tongue, and at opposite sides of the socket l' ; but at different distances therefrom are apertures k and k' , through one of which and 75 the adjacent end of the connecting-rod A, a bolt is passed to join the rod to the head eccentrically of the shaft F. In the box the shaft carries loosely a pinion, E', in engagement with the rack and having integral with 80 it one half, i , of a clutch, G, and on the same shaft is the other part, i' , of the clutch G, formed on or secured to one side of a ratchet-wheel, H, on the opposite side of which is formed or secured a double cam, I, the details 85 i' , H, and I being rigidly secured to the shaft. Above the shaft F is a stationary rod, h , supporting a dog, h' , engaging with the ratchet H, and held against lateral play between two sections of pipe, h^2 , surrounding the rod, and 90 which thus perform the function of stationary collars confining the oscillatory dog between them. In Fig. 1 this construction is intended to be represented by the termination of the two sections of pipe h^2 , respectively, at opposite sides of the annular portion or hub of the dog. The projecting end of the shaft F opposite that with which the rod A is connected carries a clutch, G', the part i^2 of 95 which is secured to the shaft, while the part i^3 is loose thereon and provided with a handle, K. The parts i and i^3 of the respective clutches

G and G' are held in normal yielding engagement with the corresponding parts i' and i'' by means of the springs f and f'.

In the box B, near its farther end, is supported transversely thereof a rock-shaft, L, having secured to it a detent, M, having a hub, g, on the shaft, a finger, g', bent at its extremity, as shown at x, which normally engages with one of the double cams I, and an arm, g², extending downward in the box past a side of the rack-bar E, which is provided near its extremity with a rigid arm, e, extending horizontally therefrom across the plane through which the arm g² extends.

15 A branch pipe, p', is joined at one end to the air-pipe p and runs therefrom through the opposite sides of the box B back to the operating-house, wherein it may terminate in a whistle, d, or communicate with any form 20 of signaling device capable of being actuated by pneumatic force. A check-valve, c, opening with the pressure of air from the supply through the pipe p, is provided in the pipe p', and near where the latter crosses the rack-bar E it contains a shut-off valve, b, having a handle, b', which extends into the path of an arm, N, for turning it with the reciprocating movements of the rack-bar, and which as a simple contrivance for the purpose (though 30 any other contrivance that will perform the object will answer and is intended to be included as within my invention) may comprise a piece of strap-iron secured to the bar E and bent to extend vertically therefrom 35 beyond the handle b', thence horizontally a distance corresponding nearly with the length of back-stroke of the rack-bar and having its free extremity bent down to extend to or beyond the horizontal plane in which the handle 40 lies.

The box B should be covered. Accordingly I provide a lid, B', flanged at its edges, which thus extend over those of the box and prevent the entrance of rain, dirt, and other foreign matter, and provided laterally with perforated ears which enter the box and through which the ear-bolts a may be passed to secure the lid in place.

45 The operation by means of compressed air is as follows: The parts are shown in the relative positions to which they are brought at the end of each operation of turning a switch when the rack-bar E is at the end of its forward stroke. In moving to the position illustrated the device N engages with the handle b' of the valve b to open the latter, thereby permitting the compressed air which has been introduced into the receiver against the rubber diaphragm D to expand it, and thus run 55 the rack-bar forward to escape the signal d and actuate the latter, thereby notifying the operator at the air-pump that the distant mechanism has performed the work of throwing the switch. The escape of the air of 60 expansion from the receiver by releasing the pressure against the diaphragm, which stretched it to the shape illustrated, permits it

to resume its normal or straight condition in the receiver C, in doing which it draws the rack-bar back to its initial position, causing 70 the device N to close the valve b. The return of the rack-bar does not rotate the shaft F, since it moves in the direction to cause the loose part of the clutch G to pass the rigid part thereof. In the back-stroke of the 75 rack-bar the arm e engages with the arm g² to rock the shaft L and raise the finger g' out of engagement with the cam I, the rise being sufficiently high to prevent the finger from again engaging with a cam till the double 80 cam-wheel has been caused to make a semi-revolution by the forward stroke of the rack-bar, which produces the following effects: When it is desired to throw a switch, air is forced into the receiver C against the diaphragm D, expanding or stretching the latter and moving the rack-bar forward, thereby 85 causing the rack to turn the pinion E', and consequently the shaft F, half-way around, which similarly turns the head F', and, 90 through the medium of the connecting-bar A, throws the switch. The holes k and k' in the head are arranged at suitable distances from the center thereof to produce either of the two desired extents of throw most common to 95 switches, depending upon which of the two holes is employed for effecting the connection with the head F' of the connecting-bar. When the switch has been thrown and the signal d actuated in the manner described, it is firmly 100 locked, both by the engagement of the pawl h' with the ratchet-wheel H, which prevents back-turning of the rotary shaft F, and, to prevent further turning of the shaft in the same direction, by the engagement of a cam 105 on the cam device I with the bent end x of the finger g.

The form of receiver C shown is best adapted to my purpose, though any other suitable form that will perform the work is included 110 as within my invention.

As will be understood from the foregoing description, a partial turn of the shaft F throws a switch in one direction, while to throw it back the turning of the shaft is continued in the same direction.

115 The handle K and clutch G' on the shaft F permit the latter to be operated by hand, when desired, a lever, O, being then applied to the rock-shaft L to turn it sufficiently to 120 raise the finger g', and thereby release the cam device I to permit the shaft F to be turned, as by forcing air into the receiver.

125 While I thus show and describe my device as operated by pneumatic force, it may as readily be operated by other mechanical means; and I wish to be understood to include as within my invention any suitable means for actuating the rack-bar, whether the means be compressed-air mechanism or 130 suitable lever mechanism.

135 What I claim as new, and desire to secure by Letters Patent, is—

1. In a railroad-switch appliance for throw-

ing a switch, the combination of a rotary shaft having connected with it eccentrically the switch connecting-bar, and revoluble in one direction to throw the switch alternately

5 in opposite directions, a reciprocating rack-bar engaging with the shaft, and means, substantially as described, connected with the rack-bar, to produce reciprocation thereof, substantially as set forth.

10 2. In a railroad-switch appliance for throwing a switch, the combination of a rotary shaft, F, having connected with it eccentrically the switch connecting-bar A and provided with a pinion, E', a reciprocating rack-bar, E, engaged by the pinion, and a clutch, G, on the shaft, substantially as described.

15 3. In a railroad-switch appliance for throwing a switch, the combination of a rotary shaft, F, having connected with it eccentrically the switch connecting-bar A and provided with a pinion, E', a reciprocating rack-bar, E, engaged by the pinion, a clutch, G, on the shaft, an air-receiver, C, having a diaphragm, D, connected with the rack-bar, and an air-condui-
20 t, p', leading to a signal, d, and provided with a valve, b, opened and closed by the reciprocation of the rack-bar, substantially as described.

25 4. In a railroad-switch appliance for throwing a switch, the combination of a rotary shaft, F, provided at one end with a head, F', with which to pivotally connect the switch-bar A, a pinion, E', on the shaft, a reciprocating rack-bar, E, engaged by the pinion, and a clutch, G, on the shaft, substantially as de-
30 scribed.

35 5. In a railroad-switch appliance for throwing a switch, the combination of a box, B, a rotary shaft, F, provided at one end with a head, F', having openings k and k' at opposite sides of and different distances from its center, and with which to pivotally connect the switch-bar A at one of the said openings,

a pinion, E', on the shaft, a reciprocating rack-bar, E, engaged by the pinion, and a clutch, G, on the shaft, substantially as de-
45 scribed.

6. In a railroad-switch appliance for throwing a switch, the combination of a box, B, a rotary shaft, F, provided at one end with a head, F', with which to pivotally connect the switch-bar A, and carrying a pinion, E', a clutch, G, a ratchet-wheel, H, and a cam, I, a reciprocating rack-bar, E, engaged by the pinion and carrying a bent arm, N, and an arm, e, a dog, h', engaging with the ratchet, a rocking detent, M, having a finger, g', normally engaging with the cam, and an arm, g², extending into the path of the arm e, an air-receiver, C, having a diaphragm, D, connected with the rack-bar, and an air-condui-
50 t, p', leading to a signal, d, and provided with a valve, b, having a handle, b', extending into the path of the arm N, substantially as described.

60 7. A railroad-switch appliance for throwing a switch, comprising, in combination, a box, B, a rotary shaft, F, provided at one end with a head, F', with which to pivotally connect the switch-bar A, and carrying a pinion, E, a clutch, G, a ratchet-wheel, H, a cam, I, a clutch, G', and a lever, K, a reciprocating rack-bar, E, engaged by the pinion and carrying a bent arm, N, and an arm, e, a dog, h', engaging with the ratchet, a rocking detent, M, having a finger, g', normally engaging with the cam, and an arm, g², extending into the path of the arm e, an air-receiver, C, having a diaphragm, D, connected with the rack-bar, and an air-condui-
65 t, p', leading to a signal, d, and provided with a valve, b, having a handle, b', ex-
70 tending into the path of the arm N, substantially as described.

MORTIMER B. MILLS.

In presence of—

J. W. DYRENFORTH,
M. J. BOWERS.
